UNITED STATES PATENT OFFICE.

WALTER JOHNISER, OF VANCOUVER, BRITISH COLUMBIA, CANADA.

RAILROAD TIE.

Application filed December 30, 1924. Serial No. 758,846.

To all whom it may concern:

Be it known that I, WALTER JOHNISER, a citizen of the United States, and a resident of the city of Vancouver, in the Province 5 of British Columbia, Canada, have invented certain new and useful Improvements in Railroad Ties, of which the following is a specification.

My invention relates to improvements in 10 railroad ties, and the object of my invention is to devise a tie of great strength capable of being easily manufactured and of being easily laid with great facility and expedition and which is of great durability so that ties 15 of this character when laid last over a long term of years and thus the frequent renewals which are necessary with ordinary wooden ties are done away with, enabling great economy in railroad track maintenance to 20 be effected.

I attain this object by the construction illustrated in the accompanying drawings in which—

Fig. 1 is a perspective view showing one 25 tie and a portion of another in place on a track.

Fig. 2 is a longitudinal sectional view taken through the tie.

Figs. 3 and 4 are detail views in perspective of the opposite rail joint connection members.

Fig. 5 is a fragmentary plan view, in part section, showing the rail joint connection members assembled.

Fig. 6 is a fragmentary plan view showing the movable clamp guide slots.

Similar figures of reference indicate similar parts throughout the several views.

The tie proper consists of a hollow body 40 formed of a plate, indicated generally by the numeral 1, with flat bottom 2 and upwardly and outwardly inclined sides and a flat cover or top plate 3 riveted to the inclined sides. At suitable points on the top plate 3 45 spaced in conformity with the gauge of the rail clamps 5 and 6 are rigidly secured by any suitable means such as riveting, clamp 5 being on the inside of one rail and clamp 6 on the outside of the other rail, and the 50 inner ends of the respective clamps are offset upwardly as at 7 and 8 respectively so as to provide a space between the clamp and the top plate 3 to permit the bottom flanges 9 of the rails 9^a to be placed between the 55 plate and the clamp, as shown more particularly in Fig. 2.

On the sides of the rails opposite to the fixed clamps 5 and 6 are placed movable clamps 10 and 11 having their inner ends 12 and 13 offset upwardly and formed similarly 60 to the inner ends of the clamps 5 and 6 so that they may engage over the bottom flanges of the rails when moved thereagainst and to the underside of each clamp 10 and 11 are rigidly secured downwardly extending 65 blocks 14 and 15 adapted for longitudinal slidable movement in slots 16 and 17 formed in the top plate 3, each of which blocks is provided with a threaded bore, 18 and 19 respectively, extending through it 70 from side to side, as indicated by the dotted lines in Fig. 2. The clamps 10 and 11 are also provided on the underside with downwardly extending pins 20—21 and 22—23 respectively slidably engaged in slots 24—25 75 and 26—27 respectively formed in the top plate, which may be headed on their lower ends, if preferred, and serve to guide and brace the clamps against lateral play during 80 their longitudinal movements when being adjusted.

28 and 29 indicate threaded rods passed through the correspondingly threaded bores 18 and 19 of the blocks 14 and 15, which rods are supported in suitable cap bearings 30— 85 31 and 32—33 respectively mounted on the underside of the plate 3 and project at their outer ends through apertures 34 and 35 in the closed ends 36 and 37 of the tie, these outer ends being squared, as at 38 and 39, 90 so that a suitable handle or wrench may be placed thereon for the operation of the rods. Lock nuts 40—41 and 42—43 are mounted on the respective rods 28 and 29 on opposite sides of the end closures 36 and 37, as shown 95 in Fig. 2, and collars 28^a—28^b and 29^a—29^b are secured to the respective rods 28 and 29 on each side of the cap bearings to hold the rods against longitudinal movement during 100 operation.

The clamps 5—6 and 10—11 described in the foregoing are for use at points intermediate the rail joints. To provide for connecting the rails at the joints the clamps are modified by the integral formation therewith or rigid attachment thereto at their inner ends of plate members 44 and 45 respectively adapted to bear on the web of the rail, plate 44 being made a part of the movable clamp indicated in Figs. 1 and 3 by the numeral 46 and 45 being made a 105 part of the fixed clamp, indicated by the 110

numeral 47 and shown in Figs. 1 and 4. The tie on which the ends of abutting rails rest is made somewhat broader than the intermediate ties and the clamps 46 and 47 are mounted thereon and operated in exactly the same manner as clamps 5-6 and 10-11. On the face of the plate 44 are two projecting pins 48 and 49 spaced to engage and pass through the holes 50 and 51 farthest from the rail joint, which holes are generally found in the rails adjacent their ends, and also to pass through correspondingly spaced holes 52 and 53 in the opposite member 45, while on the face of member 45 are two projecting pins 54 and 55 spaced to engage and pass through the rail holes 56 and 57 found adjacent the abutting rail ends and also to pass through correspondingly spaced holes 58 and 59 formed in the member 44, so that when the rails are in place and the clamps 46 and 47 tightened up the plate members 44 and 45 will grip the opposite sides of the rail web 61 while straddling the rail joint, indicated by the numeral 60 in Fig. 1, with the pins 48-49 and 54-55 passing through the rail holes from opposite sides respectively and engaging the respective holes 52-53 and 58-59, as shown more particularly in Fig. 5. The manner in which the tie is used will be readily apparent, on reference being had to the drawings, as it will be seen that if the movable clamps 10-11 and 46 be moved away from the fixed clamps 5-6 and 47 by the operation of the threaded rods 28 and 29 in the proper direction the rails may be laid on the ties when these are spaced at the proper distance apart and placed with their flanges on one side engaging under the offset inner ends of the fixed clamps and then secured most rigidly by screwing in the movable clamps until their offset inner ends engage tightly on and over the rail flanges nearest them, after which the lock nuts

40-41 and 42-43 are tightened up to prevent any slackening of the clamps through inadvertent unscrewing of the rods 28 and 29.

From the foregoing it will be seen that I have devised a rail tie which is strong and efficient, capable of being laid expeditiously and with the utmost facility, and which is characterized by great durability and lasting qualities.

What I claim as my invention is:—

1. A railroad tie comprising, a base, a fixed clamp for each rail carried by the base, a movable clamp for each rail also carried by the base between which and the fixed one the rail is disposed provided with an underside block having a threaded bore disposed slidably in a longitudinal base slot, a correspondingly threaded rod for each block extending through the threaded bore thereof, cap bearings in which the respective rods are rotatably mounted, and collars secured to said rods on each side of the respective cap bearings.

2. A railroad tie comprising, a base, a fixed clamp for abutting rail ends carried by said base, a movable clamp co-acting with the fixed clamp also carried by the base, each clamp being provided on its inner end with a plate member adapted to straddle the abutting rail end joint and bear on the webs of the abutting rails on opposite sides thereof, said plate members having pins on their inner faces adapted to extend through the said webs and into and through the plate members respectively from opposite sides when these are positioned, and means for moving and tightening the movable clamp against the rail whereby the latter is gripped between the clamps.

Dated at Vancouver, B. C., this 12th day of December, 1924.

WALTER JOHNISER.
